Des. 236,133
Patented July 29, 1975

236,133

CONTROL PANEL FOR DATA COMMUNICATION EQUIPMENT OR THE LIKE

Gary M. Kaner, Dallas, Gary C. Merritt, Carrollton, and
Barry W. Vaughn, Dallas, Tex., assignors to Carterfone
Communications Corporation, Dallas, Tex.

Filed Mar. 8, 1974, Ser. No. 449,386

Term of patent 14 years

Int. Cl. D13—03

U.S. Cl. D26—13

FIG. 1

FIG. 2

FIG. 1 is a perspective view of a first preferred embodiment of control panel for data communication equipment or the like showing our new design; and

FIG. 2 is a perspective view of an alternate embodiment of control panel for data communication equipment or the like showing our new design.

The rear view of each of the embodiments respectively illustrated in FIG. 1 and FIG. 2 is flat and unornamented; and the side views of such embodiments are the same as disclosed.

The broken lines are shown for illustrative purposes only.

We claim:

The ornamental design for a control panel for data communication equipment or the like, substantially as shown and described.
